UNITED STATES PATENT OFFICE.

ARTHUR O. DUPUY, OF CLEVELAND, OHIO, ASSIGNOR TO LANCASTER IRON WORKS, INC., OF LANCASTER, PENNSYLVANIA, A CORPORATION OF PENNSYLVANIA.

BRICKMAKING MACHINERY.

Application filed November 8, 1923. Serial No. 673,411.

This invention, relating as indicated to brick making machinery, is more particularly directed to improvements in apparatus such as pug-mills for treating or crushing 5 sand, clay or like material.

A common method of treating clay material preparatory to molding or otherwise forming it into bricks is to first put the rough clay through a disintegrator wherein 10 it is agitated to remove the larger of the stones found therein; and to then pass the clay through a pug-mill or mixer in which the material is further and more finely mixed. It has been found desirous in the 15 manufacture of certain brick or tile to still further treat the clay, and one common method therefor is to mount a pair of crusher rolls adjacent the discharge end of the pug-mill between which the clay is crushed to a 20 very fine consistency. One great difficulty in such construction is caused by the small pebbles or stones contained in clay material which wedge between rolls and quickly groove them, it being necessary to frequently 25 change and resurface them. My invention relates to a mechanism which is especially adapted to continuously remove the stones or pebbles from between the crushing rolls, thus increasing the life of the rolls and 30 greatly speeding up production.

Another object of this invention is to provide, in connection with the mechanism for removing the stones, a pivoted spout through which the clay material is delivered 35 from the pug-mill. Spouts of this nature are of less width than the rolls and direct the clay between the rolls and prevent it from overflowing the ends thereof. It has been necessary to provide a spout which 40 will properly direct the clay to the rolls and which is yieldable upon the movement of my present stone remover in forcing a stone past one side thereof.

A still further object of the invention is 45 to provide suitable mounting means for the crushing rolls so that the journals thereof will be free from the movement of the continuous stone remover and allow the stones to be discharged beyond the ends of the rolls. 50 To the accomplishment of the foregoing and related ends, said invention, then, consists of the means hereinafter fully described and particularly pointed out in the claims.

The annexed drawing and the following 55 description set forth in detail certain mecha-

nism embodying the invention, such disclosed means constituting, however, but one of various mechanical forms in which the principle of the invention may be used.

In said annexed drawings:—

Figure 1 is a side elevation of a horizontal type pug-mill showing the several novel features of my invention as embodied therein, several of the parts being broken away for the sake of clearness; Figure 2 is an end elevation as seen from the left in Figure 1; figure 3 is an enlarged fragmentary sectional view of the discharge end of the pug-mill showing in detail the pivoted spout and continuous stone remover of this invention; Figure 4 is a front elevation of the stone removing mechanism, and Figure 5 is a view similar to Figure 3 but showing a modified construction.

Pug-mills of the type illustrated in the drawing are very well known and only a brief description thereof will be given as is deemed necessary to bring out the co-operation between the operating elements of such pug-mill and the operating parts of my invention. The pug-mill proper consists of a longitudinal semi-cylindrical body member 1 supported on suitable standards 2 and having a longitudinally extending shaft 3 suitably journaled in its ends 4 and 5. Upon the shaft 3 are mounted within the member 1 the usual mixing blades (not shown) which are adapted to agitate and mix the clay material placed in the pug-mill. As is usual in such devices the blades are inclined to convey the clay from one end to the other of the pug-mill and force it through a discharge opening 6 at the front end thereof. Suitable means, such as a driven shaft 8, may be employed to actuate the shaft 3.

Mounted at the front end of the pug-mill, closely adjacent the discharge opening therein, is a pair of transverse aligned crusher rolls 10 and 11. A spout or chute surrounding the opening 6 is attached to this end of the pug-mill to direct the clay forced therethrough between the rolls. It is customary to mount such rolls that they may be adjustable with respect to one another as various conditions of the clay may require. On account of the movement of the continuous stone removing mechanism of this invention, to be hereinafter more fully described, it has been necessary to devise a mounting for the crushing rolls which will not interfere with

the operation of such mechanism in discharging stones beyond the ends of the rolls. Roll 10 is carried on a shaft 12 which has its ends received in bearings 13 secured to the rear face of the standards 2. Roll 11 is carried on a shaft 15 which is journaled in the lower ends of a pair of pivoted arms 16. Said arms are pivotally mounted upon brackets 17 secured adjacent the top of the pug-mill. Means for adjustably and yieldably positioning the rolls 10 and 11 with respect to each other consists of a pair of rods 18 pivoted at one end in the brackets 13 and having their other ends passing through apertures 19 in the lower ends of arms 16. Beyond the arms 16 adjusting nuts 20 are provided on rods 18 and compression springs 21 are located between these nuts and the face of the arms 16 to keep the roll 11 pressed toward the roll 10 under compression. It will be obvious that as the clay is fed from the pug-mill it will become intimately crushed between the rolls 10 and 11. Suitable means for driving said rolls may be provided independently of the operating mechanism for the pug-mill but for the sake of illustration I have shown the shaft 8 provided with a pulley 25 which is belted to a pulley 26 mounted on the outer end of shaft 12. As seen from Figure 2 the shafts 12 and 15 are inter-connected by gears 27 and 28 mounted on one end thereof. One advantage of driving the crusher rolls from the mechanism of the pug-mill is that the relative speed of the various elements will always be constant.

As has been previously stated, one of the great inexpediencies in passing the clay material as extruded from a pug-mill between a pair of rolls is caused by the stones or pebbles which unavoidably occur in such material, it being practically impossible to remove such stones by the ordinary types of disintegrators. Heretofore it has been found that the stones beyond a certain size will not become crushed by the rolls but will ride between the rolls and in a very short time will cause grooves in the surface thereof, and it will be apparent that upon the forming of such grooves the particular function of the rolls will be lost. Consequently, much time and expense have been consumed in changing these rolls and resurfacing them. One of the principal features of my invention has been to devise a novel mechanism which will continuously operate to remove such stones from between the crusher rolls which do not immediately pass therethrough. Such mechanism is herein shown in the form of a projecting finger 30 which is adapted to extend transversely of one of the rolls to a point close to the intersection of the V between the rolls 10 and 11. The finger 30 is carried at its upper end by a reciprocating framework 31 mounted to slide in suitable

bearings 32 which are provided on the rear face of arms 16. Means for effecting the reciprocation of frame 31 may also be connected to the operating shaft 8 of the pug-mill. At the rear end of such mill is mounted a gear or wheel 33 driven through a suitable chain 34 and sprocket 35 on the shaft 3, such wheel 33 having a crank pin 36 projecting from one side thereof to which is attached one end of a link 37. The other end of the link is connected to the lower end of an arm 38 mounted at one end of a longitudinally extending shaft 39, said shaft being mounted in suitable bearings 40 on the side of the pug-mill frame. Attached to the forward end of such rod is an arm 41, similar to the arm 39, which is connected by a link 42 to a projecting lug or pin 43 provided on the sliding member 31. It will be seen that upon rotation of the wheel 33 oscillatory movement will be imparted to the shaft 39 through the link 37 and arm 38 and the framework 31 with its projecting finger 43 will be caused to continuously traverse the surface of the rolls and remove any stone lodged therebetween.

In order that the clay coming from the pug-mill may be directed to a point close to each roll, it is necessary to provide a spout or chute at the front end of the pug-mill. Heretofore these chutes have been fixed members, but due to the operation of the reciprocating finger in this particular embodiment of my invention, I have found it necessary to devise a suitably pivoted chute which will permit of the forcing of stones beyond the side edges thereof and which will also feed the clay between the rolls without allowing it to flow beyond the sides thereof. This spout comprises a pivoted member 45 attached at the forward end of the usual chute 46, which is open at its lower and forward ends, as indicated in Figure 3 for the discharge of the clay. Although the spout is found to normally assume the correct position by gravity, it may be desirous to provide a weighted connection therewith to keep it pressed down toward the rolls.

In Figure 5 I have illustrated a mechanism which is particularly adapted to prevent all stones beyond a certain size from passing between the rolls 10 and 11. Such mechanism consists of a fixed bar or rod 50 mounted close to the point of intersection between the rolls so as to provide a restricted space between the sides of said bar and each of the rolls. It will be seen that as the clay is fed from the pug-mill this bar will keep all stones beyond a certain size from becoming wedged or crushed between the rolls. As in the first described embodiment of this invention, I also provide a continuously operating mechanism for removing the stones which collect between

the bar 50 and each of the rolls 10 and 11. A finger 51 similarly mounted upon a reciprocating frame is adapted to move transversely of the rolls. The lower end of the finger 51 is suitably bifurcated to provide projecting fingers 52 and 53 which operate on each side of the bar.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with a pug-mill having a discharge opening at one end, of a pair of crusher rolls mounted adjacent said opening, a pivotally mounted spout adapted to direct the material discharged from said opening to said rolls and a reciprocating

finger adapted to travel between said rolls and said spout, said finger being adapted to force stones lodged between said rolls to either side of said spout and beyond the ends of the rolls.

2. The combination with a pair of parallel crusher rolls, of a bar mounted parallel with said rolls close to the point of their intersection, and reciprocating means adapted to continuously traverse the space between said bar and each of said rolls.

3. The combination with a pair of crusher rolls mounted in close parallelism, of a bar located in the space between said rolls, a reciprocating member mounted parallel with said rolls and bar, and a projecting finger carried by said member, the end of said finger being bifurcated to straddle said bar.

Signed by me this 3rd day of November, 1923.

ARTHUR O. DUPUY.
